US00D949329S

(12) **United States Design Patent** (10) Patent No.: **US D949,329 S**
Jordan et al. (45) Date of Patent: **** Apr. 19, 2022**

(54) **DEVICE FOR SAMPLE COLLECTION**(71) Applicant: **Drawbridge Health, Inc.**, San Diego, CA (US)(72) Inventors: **Brett L. Jordan**, San Francisco, CA (US); **Masao Drexel**, Mountain View, CA (US); **Alicia Jackson**, Menlo Park, CA (US); **Kara Juneau**, Palo Alto, CA (US); **Dagmar Beyerlein**, San Francisco, CA (US)(73) Assignee: **DRAWBRIDGE HEALTH, INC.**, Summerville, SC (US)(**) Term: **15 Years**(21) Appl. No.: **29/740,373**(22) Filed: **Jul. 2, 2020****Related U.S. Application Data**

(63) Continuation of application No. 29/655,964, filed on Jul. 9, 2018, now Pat. No. Des. 892,310, which is a continuation of application No. PCT/US2018/013223, filed on Jan. 10, 2018.

U.S. Appl. No. 15/261,707 Office Action dated Mar. 1, 2019.
(Continued)*Primary Examiner* — David G Muller*(74) Attorney, Agent, or Firm* — Wilson Sonsini Goodrich & Rosati(57) **CLAIM**

The ornamental design for a device for sample collection, as shown and described.

DESCRIPTION

FIG. 1 is a front perspective view of the device for sample collection;

FIG. 2 is a rear view of the device for sample collection;

FIG. 3 is a front view of the device for sample collection;

FIG. 4 is a left view of the device for sample collection;

FIG. 5 is a right view of the device for sample collection;

FIG. 6 is a top view of the device for sample collection; and,

FIG. 7 is a bottom view of the device for sample collection.
